CHAIR TRAY

John J. Brazell, Baldwinsville, Mass., assignor to
E. L. Thompson Chair Corporation, Baldwins-
ville, Mass., a corporation of Massachusetts

Application September 25, 1937, Serial No. 165,727

2 Claims. (Cl. 155—126)

This invention relates to children's high chairs and particularly to trays for use with such chairs.

It is the general object of my invention to provide improved means for supporting such trays and for preventing displacement or breakage of the supporting parts.

A further object is to provide a combination of tray and support which will be pleasing in appearance and reliable and effective in use.

My invention further relates to arrangements and combinations of parts which will be herein-after described and more particularly pointed out in the appended claims.

A preferred form of the invention is shown in the drawing, in which

Fig. 1 is a plan view of a portion of a tray and support embodying my improvements;

Fig. 2 is a partial side elevation, looking in the direction of the arrow 2 in Fig. 1;

Fig. 3 is a detail sectional side elevation, taken along the line 3—3 in Fig. 1; and

Fig. 4 is a perspective view of a metal clip to be described.

Referring to the drawing, I have shown a portion of a tray 10 which is preferably formed of wood and which has a substantial thickness of stock at its rear corner portions. The tray 10 is provided with supporting arms 11, which may be pivotally secured to the back frame of a chair 30 in any convenient manner, as by screws 12.

The arms 11 are provided with cylindrical dowels 14 at their front ends, which dowels fit snugly in holes 15 of circular cross section bored into the rear corner portions of the tray 10 from the back face thereof. The dowels 14 are preferably integral with the arms and are glued in place in the holes 15 as the parts are assembled. The major part of each arm 11 is commonly of rectangular cross section.

40 The arms 11 are supported and held from turning by metal clips 20, secured to the under side of the tray 10 in any convenient manner, as by screws 21. Each clip 20 has an upwardly offset

bottom portion 22 engaging and supporting the under side of its associated arm 11, and also has upturned side portions 23 embracing said arm 11 and preventing turning of its dowel 14 in the hole 15, even in the event that the glue joint becomes 5 loosened.

It has been found in actual use that the quite troublesome breakage of arms at the points where they are joined to the tray is practically eliminated by the use of the clips 20, which clips 10 prevent any turning of the arms and the placing of excessive strain on the dowels.

The clips 20 may be polished or otherwise provided with a pleasing finish and are ornamental in appearance, in addition to their utility. 15

Having thus described my invention and the advantages thereof, I do not wish to be limited to the details herein disclosed, otherwise than as set forth in the claims, but what I claim is:

1. In association with a child's chair, a wood tray having round holes in its rear edge near the corners thereof, supporting arms rectangular in cross section and having cylindrical dowels at their front ends snugly fitting said holes and adapted to be glued therein, and metal clips secured to the under side of said tray and each having a portion extending rearwardly and offset upwardly to engage the under side of its associated arm and having up-turned side portions contacting the sides of said arm, whereby said 30 arms are supported and held from turning. 20

2. In association with a child's chair, a wood tray having round holes in the rear edge near the corners thereof, supporting arms having parallel flat sides and having cylindrical dowels 35 at their front ends snugly fitting said holes and adapted to be glued therein, and metal clips permanently secured to adjacent portions of said tray and having spaced members projecting rearward from said tray and contacting the flat 40 sides of said arms and thereby effective to hold said arms from angular displacement.

JOHN J. BRAZELL.
